Primary Examiner — W. A. Teddy Falloway(74) *Attorney, Agent, or Firm* — Vidas, Arrett & Steinkraus, P.A.(57) **CLAIM**

The ornamental design for a carrier tape, as shown and described.

DESCRIPTION

FIG. 1 is a bottom view of the carrier tape;

FIG. 2 is an isometric bottom view of the carrier tape;

FIG. 3 is a top view of the carrier tape;

FIG. 4 is an isometric top view of the carrier tape;

FIG. 5 is a front view of the carrier tape taken along the line 5-5 of FIG. 1; and,

FIG. 6 is a cross-sectional view of the carrier tape taken along the line 6-6 of FIG. 1.

The carrier tape is shown with symbolic breaks in its length, represented by jagged break lines. The appearance of any portion of the article beyond the break lines forms no part of the claimed design.
